UNITED STATES PATENT OFFICE

2,521,023

INTERLOCK STRUCTURE FOR POSTAGE
PRINTING MACHINES

Commodore D. Ryan, Los Angeles, Calif., Frank P. Sager, deceased, late of Alhambra, Calif., by Harry L. Sager, executor, Alhambra, and Herschel L. Atherton and Ernest R. Bergmark, Los Angeles, Calif., assignors to Commercial Controls Corporation, a corporation of Delaware

Original application April 29, 1940, Serial No. 332,305. Divided and this application December 1, 1944, Serial No. 566,070

3 Claims. (Cl. 101—91)

1

This invention relates to a mail treating machine, and more particularly to an envelope sealing mechanism therefor, together with locking mechanism to prevent fraudulent use of the postage printing device incorporated in such machine.

A mail treating machine, to be commercially acceptable, should, among other things, be capable of sealing and stamping envelopes at a high rate of speed in order to be capable of handling a large amount of mail in a relatively short time. In spite of such high speed operation, however, it is of utmost importance that the envelopes not only be securely sealed to prevent tampering of the contents thereof, but also that the postage printing mechanism, i. e. the postage meter, be so locked during the stamping and sealing operations as positively to preclude the taking of fraudulent impressions from the printing die.

Machines of this character usually include what might be termed a power unit, which supports and drives the meter. The meter is usually of such a character that when it is in normal or rest position, i. e. when the value printing die is in its rest position at the beginning of the printing cycle, the die is inaccessible whether the meter is on or off at the power unit, and accordingly not available for fraudulent use. When, however, the die is in the printing position, during its cycle of operation, it would be available for fraudulent use were it possible to detach the meter from the power unit at this point of its operating cycle. It is accordingly among the objects of this invention to provide a mail treating machine capable of efficiently sealing envelopes, and also capable of preventing fraudulent use of the postage printing meter. Other objects will be in part apparent and in part pointed out hereinafter.

The invention accordingly consists in the features of construction, combinations of elements and arrangements of parts as will be exemplified in the structure to be hereinafter described, and the scope of the application of which will be indicated in the following claims.

In the drawing, wherein we have shown one embodiment of our invention,

Figure 1 is a perspective view of the machine;

Figure 2 is a fragmentary sectional elevation illustrating the retractable sealing roller;

Figure 3 is an enlarged sectional view taken along the line 3—3 of Figure 1, and illustrative of the relation between the final sealing roller and the printing drum;

Figure 4 is a section taken along the line 4—4 of Figure 3;

2

Figure 5 corresponds generally to Figure 3, except that Figure 5 includes a portion of the tape feeding device and illustrates the manner in which the pressure roller is automatically released to swing to its retracted position, as shown in dotted lines, when the tape feeding device is moved to its operative feeding position;

Figure 6 is an enlarged fragmental sectional view taken along the line 6—6 of Figure 8, to show the manner in which the meter is mounted on the power unit just prior to clamping the meter into its operative position;

Figure 7 is a view similar to Figure 6, which shows a meter locked in its operative position on the power unit;

Figure 8 is a sectional elevation taken at right angles to the section shown in Figure 2, showing the right-hand end of the machine from which the end cover plate has been removed, and showing in greater detail the meter locking mechanism shown in dotted lines in Figures 6 and 7, and also showing the mechanism which releases the sealing roller for movement into its retracted position when the meter is unlocked from the power unit;

Figure 9 is a fragmentary developed diagrammatic view of an interlock which disables the clutch tripping mechanism when the meter is removed from the power unit;

Figure 9A is a fragmentary sectional view taken substantially along the line 9A—9A of Figure 2;

Figure 10 is a fragmentary vertical section through the meter, showing the meter locking and positioning device;

Figure 11 is a fragmentary vertical section taken substantially along the line 11—11 of Figure 10;

Figure 11A is a fragmentary vertical section taken through the meter substantially along the line 11A—11A of Figure 10;

Figure 12 is a composite view illustrating one of the meter interlocks by which the clutch tripping mechanism is disabled when the meter is removed from the power unit;

Figure 13 is a fragmentary vertical section showing the meter lock in its unlocked position; and,

Figure 14 is similar to Figure 13, but illustrates the meter lock in its locked position.

Similar reference characters refer to similar parts throughout the various views of the drawing.

This application is a division of the co-pending application of Frank P. Sager et al., Serial No. 332,305, filed April 29, 1940 which issued on March 6, 1945 as Patent No. 2,371,070. The said

Sager et al. application discloses a mail treating machine which is an all purpose machine, i. e. a machine readily adjusted to treating all types or classes of mail matter, including first, second and third class mail, registered mail and parcel post, and for printing any one of a wide range of postage values for all of the above classes of mail matter in parcel post. The machine is capable of treating the above classes of mail matter at high speed and under full control and protection against waste of postage or unauthorized use and may be easily and conveniently adjusted to seal and stamp, or stamp without sealing, or seal without stamping envelopes of various lengths, widths and thicknesses.

The description to follow will, accordingly, be directed primarily to the final sealing and ejecting mechanism which receives envelopes subsequent to the printing operation, and seals and ejects them into a suitable receptacle; to a locking mechanism by which the control mechanism of the power unit is locked when the meter is unlocked for removal from the power unit; and to an inter-lock device by which the meter is locked onto the power unit during the printing cycle to prevent removal thereof for fraudulent use.

As shown in Figure 1, the machine includes generally the following major elements and instrumentalities which, for convenience, are identified by the general reference numerals preceding each: 150, frame structure; 151, feeding hopper; 152, stripper; 153, conveyor feeding system for the mail matter; 154, envelope flap moistening device; 155, power plant and driving mechanism; 156, tape feeding device; 157, meter; 158, ink feeding mechanism for the meter; 310, final sealing and ejecting device.

In general, the operation of the machine, when adjusted to seal and stamp envelopes, is as follows: A stack of envelopes 166 is placed within feeding hopper 151 and is fed therefrom one by one by a feeding device (not shown) through stripper 152 which assures delivery of the envelopes individually to conveyor 153. The conveyor delivers the envelopes to the printing drum of meter 157 which stamps the proper postage value on the envelope and delivers it to the final sealing and ejecting device 310. This device securely presses the moistened flap of the envelope against the envelope back to assure a tight seal therebetween, and delivers the sealed and stamped envelope into a receiving hopper generally indicated at 311.

As shown in Figure 3, the final sealing and ejecting device 310 includes a driven rubber-tired roller 338 carried by a shaft 339 journaled in a bracket 340 suitably fastened to the left side cover plate 341 of frame 150 (Figure 1). Referring back to Figure 3, the machine is provided with a platen 329 rotatably mounted on a shaft 326 disposed below the printing drum 332 of the meter. Shaft 326 (Figure 2) carries a step pulley 244, while shaft 339 has fastened thereto a pulley 343, pulleys 244 and 343 being connected by a driving belt 344. Shaft 326 is driven by the power unit of the machine, and accordingly this shaft, through the medium of belt 344, drives shaft 339 and accordingly the rubber-tired roller 338 over which the envelopes pass, as shown in Figure 3. Thus, when an envelope is delivered to roller 338 by platen 329, the advance of the envelope is continued subsequent to its passing from between platen 329 and printing drum 332 by roller 339 which finally ejects the envelope into receiving hopper 311 (Figure 1). As shown

in Figure 2, we preferably provide a belt tightening roller 345 which is mounted on the underside of an envelope supporting plate 336, and which acts to maintain sufficient tension in the driving belt 344.

Cooperating with roller 338 (Figures 3 and 4) are a pair of spring-weighted pressure rollers, the first of which may be referred to as a creasing roller 346 (Figure 4) and the second of which may be referred to as a sealing roller 347. The creasing roller 346 is relatively narrow in width to engage only the flap edge of the envelope and press it against rubber roller 338 to complete the creasing and assist in the sealing of the flap. Sealing roller 347 is of greater width and firmly presses the envelope against rubber roller 338 to press the moistened flap of the envelope against the body thereof to effect the final sealing. This roller organization also operates to eject the treated mail matter from the machine.

To prevent sealing roller 347 from contacting the newly printed stamp on the envelope and thereby smearing the impression, portion 348 thereof is of sufficiently reduced diameter to clear the newly printed stamp.

Creasing roller 346 is swingably mounted with relation to the main sealing roller 338 to provide for different thicknesses of mail matter passing between these two rollers. Thus, creasing roller 336 is rotatably mounted in the bifurcated free end of a hinge plate 349 the bifurcations of the plate being bent to form vertical bearing flanges 350. An axle 351, carried by bearing flanges 350, rotatably supports creasing roller 346. The left-hand end of swing plate 349, as viewed in Figure 4, is bent to form a pair of spaced vertical flanges 352 for hingedly mounting this end of the plate to a hinge pin 353, which pin is supported in a bracket 354 (see also Figure 3).

A torsion spring 355 (Figure 4) encircles hinge pin 353 and acts between the hinge plate and bracket to yieldingly urge creasing roller 346 against sealing roller 338. The innermost of the two bearing flanges 350 is flanged rearwardly to provide a stop lug 356, which lug overhangs an offset portion 357 of bracket 354. Screw threaded into this portion of the bracket is an adjusting screw 358 against which the stop lug 356 engages to hold the creasing roller in proper clearance relation with respect to sealing roller 338. This clearance is just sufficient to hold the corresponding roller out of driving engagement with the sealing roller so as not to wear unduly or deform the rubber surface of the sealing roller.

A similar type of hinge plate 359 is provided for swingably supporting roller 347 from bracket 354, the hinge plate being provided at its free end with spaced bearing flanges 360 for pivotally supporting a roller shaft 361 on which roller 347 is mounted. The other end of hinge plate 359 has a pair of integral flanges 362 which pivotally mount the plate on hinge pin 353. A torsion spring 363 surrounds hinge pin 353 between flanges 362 and acts between the plate and bracket 354 to yieldingly urge roller 347 toward the main sealing roller 338. Roller 347 is maintained in the same clearance relation with respect to main sealing roller 338, as described for creasing roller 346, by providing hinge plate 359 with an offset lug 364 which overlies, so as to rest upon, the upper surface of creasing roller hinge plate 349. As this lug overlies hinge plate 359, it does not prevent roller 347 from being lifted due to irregularities of the mail matter independently of the creasing roller 346.

5

When the machine is adjusted to print postage indicia upon gummed tape, it is desirable to automatically retract the creasing and pressure rollers 346 and 347 to the broken line position shown in Figure 5, and for this purpose bracket 354 is hinged to the supporting bracket 340 by a pin 365. A latch member 366 is pivotally mounted on bracket 354 by a hinge pin 367, and is provided with a latch notch 368 (see also Figure 3) engaging a latch plate 369 (Figure 5) securely fastened on the inner face of the main supporting bracket 340. In order to yieldingly maintain the latch member in latching relation with plate 369, a compression spring 370 is interposed between a latch finger 371 and a suitable bore formed in the main supporting bracket 340. The latch member is notched as shown at 372, and a stop pin 373 carried by bracket 354 cooperates with notch 372 to limit the swinging motion in either direction of latch member 366. The latch member is utilized to support a guide plate 374 which operates to guide the envelopes or other mailing matter from platen 329 to the final sealing and ejecting device 310. Guide plate 374 is preferably formed as shown in Figures 3, 4 and 5.

A retracting spring 375 (Figure 5) is mounted within a hole 376 drilled in bracket member 354. The end of spring 375 which engages the inner end of bore 376 is enlarged to frictionally bind the spring within the bore while the free end of the spring extends a short distance beyond bracket 354 to engage the main supporting bracket 340 when bracket 354 is in its latched position and acts upon release of latch member 366 to supply the force necessary to swing bracket member 354 to the retracted position shown in broken lines in Figure 5. In Figure 5 the free end of the retracting spring 375 is shown projecting from bracket member 354 when swung to its retracted position.

The sealing and ejecting device 310 is manually returned to its normal operating position, but may be tripped automatically to swing to its retracted position, as shown in Figure 5, upon removal of the meter, or when the tape feeding device is shifted from its non-printing to its printing position in a manner later to be described.

As described in detail in the above-noted Sager et al. application, the machine is provided with a tape feeding device manually shiftable into and out of operative position by the handle 156 (Figure 1) and this tape feeding device is formed as an integral part of the machine. As will be described in detail, manipulation of the tape feeding device to its operative position automatically causes the retracting of the sealing and ejecting device 310 (Figure 5) to its broken line position. As described in the said Sager et al. application, the tape feeding device includes the mechanism shown in Figure 5 herein, which is operated upon rotation of a shaft 661 upon manipulation of the tape feeding device. Rotation of this shaft rocks an arm 666 which, in turn, causes a link 743 to rise. Connected to this link is a bearing 791 which is also raised when the tape feeding device is lifted into printing position. This bearing 791, upon lifting of the tape feeding device into printing position, engages latch member 366 and lifts the latch until it is released from its latch plate 369, whereupon frame 354 swings to its broken line position in the manner previously described. Thus it appears that when the tape feeding device is raised

6

to its operative position, it automatically releases the sealing and ejecting device 310 from its operative position so that the device may be retracted into its inoperative position, as this portion of the machine is of no utility during the operation of the tape feeding device, i. e. when the machine is adjusted to print postage on the tape.

As pointed out hereinabove, it is also desirable that the sealing and ejecting device 310 (Figure 1) be retracted to its inoperative position when the meter 157 is unlocked. To this end, it will be necessary to describe certain portions of the meter, a detailed description of which is set forth in the above-noted Sager et al. application.

The meter is, in general, a rectangular structure and its operating parts are entirely enclosed and protected by suitable covers and housings. As shown in Figure 1, the meter is provided with a handle 979 to enable the meter to be conveniently installed on and removed from the power unit.

As shown in Figures 10 and 11, the bottom surface of the meter is provided with a forward positioning and locking pin 983, and two spaced rear positioning and locking pins 984 and 985 (see also Figure 6). Each of these pins is provided with an annular locking groove 986 (Figure 11) by means of which the meter is positioned and locked in driving registry with the power unit portion of the machine.

The power unit is provided with a meter supporting plate 970 (Figures 6 and 8) which plate at its forward end is mounted on the upper surface of a meter supporting bracket 162. The bracket is provided with bosses 987 to which supporting plate 970 is securely fastened by screws 988. The rear end of plate 970 is securely fastened to suitable blocks 989 which are, in turn, fastened to a bracket 163 (Figure 6). Metering supporting plate 970 is provided, as shown in Figure 6, with three spaced openings 992, 993 and 994, which openings are more or less egg-shaped, and through which three meter locking pins 983, 984 and 985 extend when the meter is mounted on the power unit.

When mounting the meter on its supporting plate 970, its three locking pins are entered into the larger end of the three openings 992, 993 and 994, and means are provided for shifting the meter until its pins engage the smaller ends of said openings. The meter is provided with a positioning pin 995 (Figures 6, 7 and 10) which extends through an elongated opening 996 (Figure 6) formed in plate 970 against which pin a meter positioning and locking lever 997 engages during the rotation of said lever about its pivot pin 998 to shift the meter from its mounting position, as shown in Figure 6, to its locked operative position, as shown in Figure 7.

The means for operating the meter positioning and locking lever 997 includes a crank handle 999 (Figure 6) pivotally mounted on bracket 163 by a pivot bolt 1000. As shown in Figure 8, a crank arm 1001 has one end connected to pivot bolt 1000 and the other end connected by means of a gooseneck 1009 to a connecting rod 1002. The forward end of rod 1002 is pivotally connected to the meter positioning and locking lever 997 by a ball joint 1003. This ball joint may include a ball-like member 1004 slidably mounted on the connecting rod in position to engage a semi-spherical surface 1005 formed on lever 997. A compression spring 1006 is interposed between

ball member 104 and a collar 1007, which collar is securely fastened to the forward end of the connecting rod. The compression spring is arranged to yieldingly urge lever 997 against a connecting rod stop collar 1008, which collar is securely fastened on connecting rod 1002.

By means of the above-described construction, the meter positioning and locking lever 997 is positively returned to its unlocked position, as shown in Figure 6, by connecting rod collar 1008 directly engaging the positioning and locking lever 997.

The rotation of crank handle 899 from its retracted position of Figure 6 to its locking position of Figure 7, will through its connecting mechanism rotate the meter positioning and locking lever 997 in a counterclockwise direction, and during this rotation will engage the meter positioning pin 995 to move the meter into its operative locked position. The movement of the meter into its operative position shown in Figure 7, is employed to lock the meter to its supporting plate 970 by providing adjacent the smaller end of each of the three openings 992, 993 and 994, respectively, locking members 1010, 1011 and 1012, each of which is provided with a cam surface 1013 (Figures 7 and 10) for engaging the annular locking notches 986 formed in the metering positioning and locking pins. The engaging surfaces formed between the locking members and meter pins are preferably tapered, as shown, for drawing the meter down tightly onto plate 970 when the meter is moved into its locked position. The locking members may be fastened to the under surface 35 of meter supporting plate 970 by rivets 1014 (Figure 6).

Thus the meter may be placed onto its supporting plate 970 and then moved rearwardly and to the left, as viewed in Figures 6 and 7, along the surface of the plate and into its operative position. To remove the meter from the power unit, this procedure is reversed. The horizontal movement of the meter to or from its operating position is employed to connect or disconnect the meter driving coupling 982. In Figure 6 this coupling is shown disconnected and the meter ready to be lifted from the power unit, whereas in Figure 7 the coupling is shown connected and the meter is in its normal driving position.

The meter locking system includes among others a key lock for locking the machine against unauthorized use. As shown in Figures 1, 11a, 13 and 14, a key operated tumbler lock 1514 (Figure 1) extends through a suitable bore 1515 (Figure 11a) formed in the side wall of meter housing 1373, and is securely fastened within the bore by a flange 1516 formed on the forward end of the lock barrel. A lock nut 1517 is also threaded on the lock barrel, and it, together with the flange 1516, clamps the lock barrel within the bore 1515 in position. Lock 1514 is secured against rotation within bore 1515 by a radially extending pin (not shown) secured to the lock barrel and extending therefrom into a key way (not shown) formed in the housing bore 1515. The rotative core portion 1520 of the lock is provided with the usual key slot to receive a key for rotating the core element. The inner end of the lock core has a stop plate 1522 for engaging a stop pin 1523 (Figure 13) when the lock is in its unlocked position, as shown in Figure 13, and a stop pin 1524 when turned to its locked position, as shown in Figure 14. To

yieldingly maintain the lock in its unlocked position, as in Figure 13, a spring 1525 is interposed between the stop plate 1522 and a bracket 1526 secured to housing 1373 by screws 1521. A lock actuating pin 1528 extends outwardly from the lock plate to engage a stud 1529 projecting radially from control shaft 1492 into which the pin is screw-threaded and securely retained by a lock nut 1530.

It may now be observed that when the lock is rotated from its unlocked position in Figure 13 to its locked position in Figure 14, lock actuating pin 1528 engages control shaft stud 1529 to rotate the shaft counterclockwise to the locking position shown in Figure 14. A locking finger 1531 (Figure 12) is securely keyed to control shaft 1492. Rotation of control shaft 1492, as described, swings locking finger 1531 into mesh with a locking notch 1533 formed in the periphery of a locking collar 1534 which is securely fastened to a countershaft 1044 by a taper pin 1535, thereby locking the countershaft against rotation. As this countershaft (see above-noted Sager et al. application) is at all times connected to the main driving shaft of the meter through a train of gears (not shown) the main shaft of the meter is thereby securely locked against rotation.

In order to prevent possible damage to both the power unit and meter, the locking device described is provided with mechanism for rendering the meter driving clutch tripping mechanism inoperative whenever the locking device is actuated to lock the meter against unauthorized use.

As shown in Figures 11a and 12, control shaft 1492 is provided with a collar 1493 from which extends an actuating finger 1536 positioned to engage the upper end of a push rod 1537 (Figure 12) so that when the control shaft is rotated the push rod is forced downwardly as viewed in Figure 12 when the locking mechanism is actuated to lock the meter. This push rod is slidably mounted in bearing lugs 1538 suitably carried by the meter frame side plate. A head screw 1539 is screw threaded on the lower end of push rod 1537 and locked thereon by means of a lock nut 1540. Push rod head 1539 engages the free end of a crank arm 1541 which is fastened to one end of a sleeve 1542 journaled on a cross shaft 1543 suitably supported at its opposite ends in the meter side plates. Securely mounted on the opposite end of sleeve 1542 is a second crank arm 1544, the free end of which engages a shoulder 1545 formed on the lower end of a plunger 1546. This plunger is slidably mounted in a block 1547 mounted on a flanged stud 1548 between the flange 1549 of the stud and a nut 1550 screw threaded upon the end of said stud. Block 1547 is held against rotation by a dowel pin 1551 extending into a suitable bore formed in the flanged portion of the stud. Plunger 1546 is yieldingly urged downwardly by a compression spring 1552 placed between the plunger and the head portion of block 1547. Preferably plunger 1546 is hollowed out at its upper end to receive the lower end of spring 1552. The lower end of plunger 1546 is reduced as at 1553 and this end engages the head 1554 of a pin 1555 extending through a bushing 1556 mounted in a bore 1557 formed in the meter base plate 1558. Each side of plunger block 1547 is cut away to provide operating clearance for the end of crank arm 1544 to engage a shoulder of the plunger.

Still referring to Figure 12, meter supporting plate 970 has secured thereto a sleeve 1560 within which a plunger 1559 is slidably mounted, the plunger being provided with an annular groove 1561 and the sleeve with a screw 1561a, the point of which enters the plunger groove to limit the extent of vertical movement of the plunger. The lower portion of sleeve 1560 has a longitudinal slot through which extends arm 1563 of a lever generally indicated at 1564. The lower end of plunger 1559 is rounded and engages the free edge of lever arm 1563. Lever 1564 is pivotally connected to a bracket 1565 by a pin 1566 the bracket being secured to the front face of bracket 1563 (see Figure 9) in any suitable manner. Referring back to Figure 12, lever 1564 includes an arm 1567, connected to the upper end of a control link 1568 (Figure 9) by a pivot pin 1569. The intermediate portion of the control link is swingably supported from bracket 1565 by a link 1570 pivoted at its ends respectively to bracket 1565 and link 1568. The lower end of control link 1568 has a horizontally extending foot 1573 which overlies a floating pin link 593, as shown in Figure 9. A compression spring 1574 is interposed between link 1570 and a bar 1575 projecting rearwardly from bracket 1565 and securely fastened therein by a taper pin 1576. A spring retaining pin 1577 extends upwardly from link 1570 through the spring 1574 to prevent it from buckling, the upper end of the spring being confined within a hole 1578 formed in bar 1575. Screw threaded through the forward end of bar 1575 is a stop screw 1579 for limiting the clockwise rotation of lever 1564, as viewed in Figure 9. This stop screw is securely fastened in its adjusted position by a lock nut 1580.

The position of the parts just described in Figure 9 illustrates these parts as they would appear when the clutch tripping mechanism in the power unit is conditioned for normal operation. When the meter is locked by its key locking device 1514 (Figure 1) this key locking device operates to release lever 1564 (Figures 9 and 12) for clockwise rotation, as viewed in Figure 9, under the influence of compression spring 1574.

Clockwise rotation of lever 1564 depresses control link 1568 so that its foot 1573 engages pin 593 to force the forward end of a link 592 to which the pin is connected downwardly until a shoulder 605 thereon is well below the contact surface 606 of a trip lever 549. With these parts in this position, an attempt at actuation of the tripping mechanism for clutch 526 which drives the meter, either by the envelope tripping mechanism or the manual tripping mechanism described in the said Sager et al. application, will not result in tripping the clutch, as shoulders 605 and 606 are sufficiently separated so that movement of link 592 to the left will not result in clockwise movement of trip lever 549. Without such movement of the trip lever, clutch 526 will not engage. Hence, it may be seen that locking of the meter through locking mechanism 1514 (Figure 1) effectively prevents purposeful or inadvertent engagement of clutch 526.

When the meter is unlocked by means of lock 1514, as described above, lever 1564 (Figure 9) is rocked counterclockwise to lift control lever foot 1573 and thereby permit the forward end of floating link 592 to return to its normal operative position wherein its shoulder 605 can engage shoulder 606 on the clutch tripping lever 549. Hence the tripping operation is effected manually or by reason of the passage of an envelope through

the machine, movement of link 592 thereby to the left will result in clockwise movement of tripping lever 549 to effect engagement of clutch 526 and accordingly cause the meter to be driven.

From the above, it follows that whenever the meter is locked by lock 1514 the lock not only operates to lock the meter against rotation but simultaneously therewith renders the power unit tripping mechanism inoperative, thereby making it impossible to trip the meter clutch into operation while the meter is locked. It follows that upon release of the meter key lock 1514, the driving mechanism of the meter is released, and at the same time the clutch tripping mechanism of the power unit is returned to its operative condition. For a more detailed description of the clutch tripping mechanism, reference is made to Figure 33 of the above-noted Sager et al. application.

In the event that the driving mechanism of the meter or power unit should become jammed or stuck during the operating cycle of the machine, we have provided emergency means for releasing the meter from the power unit under such circumstances. As shown in Figures 6, 7, 11 and 11A, meter supporting plate 970 (Figure 11A) is provided with a disc 1671 journaled in a suitable bore 1672 extending through the supporting plate so that the free surface of the disc is flush with the top surface of the plate. This disc is provided adjacent its lower surface with a flange against which the heads of rivets 1673 bear to support the disc in its proper operating position. Thus the flanged portion of disc 1671 is retained between the heads of rivets 1673 and the bottom surface of the meter supporting plate 970.

In order to assemble disc 1671, its flanged portion is provided with two notches 1674 (Figure 7) positioned to register with the heads of rivets 1673 in order to permit the disc to be inserted into bore 1672 when the disc is turned to an extreme inoperative position. The disc has an arm 1675 provided with a right angled end portion 1676 which is secured to a post 1677 by a headed locking pin 1678 which extends through aligned bores formed in the post end portion 1676 of the arm. Post 1677 is securely riveted to the under surface of plate 970. The end of pin 1678 has a hole therein through which a wire 1679 is passed. The ends of this wire are fastened together by means of a lead seal 1680 which is applied by an official of the post office department.

A conical depression 1681 (Figure 11A) is provided in the upper surface of disc 1671 eccentric to the axis of rotation thereof to receive the point 1669 of a plunger 1657 when the meter is locked in its operative position.

During the removal of the meter from the power unit, the tapered surfaces of plunger point 1669 and conical depression 1681 will cam the plunger upwardly against the tension of its spring 1658. This upward movement of the plunger causes bellcrank 1662 to rotate about its pivot counterclockwise, as viewed in Figure 11A, and as the meter driving mechanism is in its rest position, the locking finger 1664 of the bellcrank lever may enter a locking disc notch 1666 to lock the meter. However, should it be attempted to remove the meter from the power plant while the driving mechanism of the meter is in some other position than its normal rest position, the end of locking finger 1664 will engage the periphery of the locking disc in which notch 1666 is formed, thereby preventing the camming of the end of plunger 1658 from the conical depression 1681. As a result of this,

the meter cannot be removed from the machine until the parts are returned to their rest position. When the parts are in this position, it is impossible to gain access to the printing die of the meter, and accordingly the making of fraudulent impressions therefrom is precluded.

In the event that the mechanism in the meter or the power unit becomes inoperative through jamming when the parts are out of their normal rest position, it is impossible to remove the meter from the power unit in the normal manner. Under such circumstances, the services of an authorized official are necessitated to break seal 1680, remove wire 1679 from the end of pin 1678 and withdraw the pin from end 1679 of disc arm 1675. This permits rotation of the disc by means of manipulating arm 1675 while simultaneously actuating the metering locking crank handle 999 to permit the pointed end 1669 (Figure 11A) of plunger 1658 to travel during the movement of the locking and positioning pins along their respective slots until the pins are free of their respective locking members, whereupon the meter may be lifted from the power plant.

It is important to prevent operation of the power unit meter driving mechanism during such time as the meter is being mounted on the power plant or removed therefrom, in order to prevent possible injury to either the power plant, meter or both. To this end, the meter positioning and locking lever 997 (Figure 6) is provided with an arm 1915 having an upturned finger portion 1916, the upper end of which is inclined to provide a cammed surface 1917, as shown in Figure 9A. Cam surface 1917 is arranged to cooperate with a similarly inclined cam surface 1918 formed on the forward end of lever 1564 to lift the forward end of this lever in the manner shown in Figure 9A, when the meter positioning and locking lever 997 is moved to its meter releasing position, as shown in this figure, and also in Figure 6. Lifting of the forward end of lever 1564 effects rotation of the lever clockwise, as viewed in Figure 9, to render the clutch tripping mechanism inoperative, as heretofore described.

Rotation of the meter positioning and locking lever 997 (Figure 6) operates to position and lock the meter in correct operating alignment with the power unit, and upon completion of this operation, the inclined cam surface 1917 (Figure 9) carried by the locking lever, moves to permit rotation of lever 1564 in a clockwise direction as viewed in Figure 9, thereby returning the clutch operating mechanism to an operative condition as also previously described.

Hereinbefore we have described the construction and operation of the final sealing and ejecting device 310 (shown in Figures 1, 3, 4 and 5) and it was pointed out during this description how bracket 354 of the device is latched in its operative position, and the manner in which the bracket is automatically unlatched during the lifting of the tape feeding mechanism into printing position to permit the bracket to swing from its full line to its broken line position, as shown in Figure 5. Bracket 354 of the sealing and ejecting device 310 should be in its operative position, as shown in Figure 1, when printing stamps on envelopes or upon sealing of such envelopes.

The meter positioning and locking mechanism heretofore described is provided with means for automatically unlatching bracket 354 to permit the bracket to swing from its operative to its inoperative position when the meter is released for

removal from the power unit. To this end a trip lever 1919 (Figures 6, 7 and 8) is pivotally mounted intermediate its ends by means of a pin 1920 (Figure 6) on a bracket 1921 secured to the meter supporting frame 162 (Figure 8) by means of screw 1922. Lever 1919 is provided at its rear end with an inclined cam surface 1923 disposed intermediate to stop surfaces 1924 and 1925 for cooperation with a cam plate 1926 (Figure 8) secured to positioning and locking lever 997 by screws 1927 (Figure 7). As shown in Figure 8, the trip lever stop surface 1925 will engage the positioning lever cam plate 1926 when the meter is locked in its operative position. With the trip lever so positioned, the forward end of said lever directly underlies latch member 366 (Figure 3) of the sealing and ejecting device 310 when the bracket 354 is in its operative position.

Rearward movement of crank handle 999 (Figure 6) to unlock the meter from the power plant rotates lever 997 clockwise, as viewed in Figure 7, whereupon its cam plate 1926 engages the inclined cam surface 1923 of the trip lever, causing said lever to rotate clockwise, as viewed in Figure 8. This movement lifts the forward end of trip lever 1919, and as a result lifts bracket latch 336 (Figure 3) to release the bracket for movement to its retracted position, as shown in dotted lines in Figure 5. When the crank handle 999 (Figure 6) has been moved to its rearmost position to unlock the meter for removal, locking lever 997 will have carried its cam plate 1926 (Figure 8) into engagement with the trip lever stop surface 1924, and will thereby maintain the trip lever in its tripping position to prevent relatching of the sealing and ejecting bracket 354 (Figure 5) in its operative position. This mechanism accordingly automatically releases bracket 354 of the sealing and ejecting device out of the way to prevent possible damage to such mechanism while removing or mounting the meter on the power plant.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

We claim:

1. In a mail treating machine, in combination, a power unit having a meter supporting platform, a meter unit having a base plate adapted to rest on said platform when the meter unit is detachably installed thereon, cooperating formations on said platform and base plate for holding said meter unit in position thereon, manually operable means on one of said units and engageable with a portion of the other of said units for effecting relative movement between said units to effectuate the holding relation of said cooperating formations, said manually operable means being on said power unit and including a lever, and a pin extending from said meter into a slot formed in the platform of said power unit and in the path of said lever so that upon operation of said manually operable means said lever is swung against said pin to move said meter relative to said power unit.
2. In a mail treating machine, in combination, a power unit adapted to detachably support a meter, manually operable meter locking means on said power unit, an ejecting and sealing roller unit, means pivotally mounting said roller unit on said power unit for move-

ment into and out of operative position, means for latching said roller unit in operative position, and means operated by said manually operable means upon operation thereof into unlocking position for unlatching said roller unit to permit retraction thereof to its inoperative position.

3. In a mail treating machine having a removable meter, and a pair of opposed final sealing rollers one of which is retractable; means for locking the removable meter in operative position on the machine, and means operated during the actuation of said locking means to release the meter for removal for causing the retractable sealing roller to be retracted.

COMMODORE D. RYAN.
